CLAIM

The ornamental design for an LED light fixture, as shown and described.

DESCRIPTION

FIG. 1 is a bottom perspective view of a first embodiment of an LED light fixture showing our new design, comprising an LED module and a reflector;

FIG. 2 is a bottom view thereof;

FIG. 3 is a bottom perspective view thereof without the reflector;

FIG. 4 is an enlarged bottom view of the LED module of the first embodiment;

FIG. 5 is a side view thereof, the opposite side being identical;

FIG. 6 is a bottom view of a second embodiment of an LED light fixture, comprising an LED module and a reflector;

FIG. 7 is a bottom perspective view thereof without the reflector;

FIG. 8 is an enlarged bottom view of the LED module of the second embodiment; and,

FIG. 9 is a side view thereof, the opposite side being identical. The broken lines are for the purpose of illustrating portions of the LED light fixture and form no part of the claimed design.
